UNITED STATES PATENT OFFICE.

BENJAMIN H. ANIBAL, OF DETROIT, MICHIGAN, ASSIGNOR TO THE STUDEBAKER CORPORATION, OF DETROIT, MICHIGAN, A CORPORATION OF NEW JERSEY.

INSTRUMENT PANEL.

Application filed October 1, 1924. Serial No. 740,969.

This invention relates to improvements in vehicle bodies and refers particularly to instrument mountings therein in which one or more instruments are mounted on a panel secured to the instrument board forming a part of the body.

It is an object of this invention to provide a removable face or scroll plate for an instrument panel.

10 It is another object to provide an instrument panel construction in which the instruments are independently supported on a panel provided with a readily removable and replaceable finishing scroll or face-plate, 15 which construction allows the finish of the panel to be readily changed, by changing the scroll plate, to match the finish of the panel support.

20 A further object is to provide a panel which will receive a plurality of conventional or standard instruments such as are employed in single and independent mounting without a panel, which instruments are provided with independent glass covers 25 and are independently mounted upon the panel, the panel being provided with a readily removable finishing face or scroll plate and a glass cover which extends over and covers the faces of all the instruments.

30 The above being among the objects of the present invention the same consists of certain features of construction and combinations of parts to be hereinafter described with reference to the accompanying drawings and then claimed, having the above and other objects in view.

In the accompanying drawings which show a suitable embodiment of the present invention, and in which like numerals refer 40 to like parts throughout the several views,

Figure 1 is a face view of an assembled instrument panel mounted upon an automobile instrument board.

Figure 2 is an enlarged sectional view 45 taken on the line 2—2 of Figure 1.

Figure 3 is a face view of the finishing scroll or face plate only.

Figure 4 is an enlarged section of the 50 finishing scroll or face plate taken on the line 4—4 of Figure 3.

Figure 5 is a face view of the instrument supporting panel only.

Figure 6 is an edge view of the instrument supporting panel shown in Figure 5.

55 Figure 7 is a view from the back of the

panel of the lamp receiving shell or socket.

Figure 8 is a broken sectional view taken on the line 8—8 of Figure 1, which view includes a section of the supporting panel taken on the line A—A of Figure 5, and shows a modified method of securing the instruments to the panel to prevent unauthorized removal, and the method of fastening the panel to the instrument board.

In the drawings is shown an instrument 65 board 10 of the type commonly used on automobiles comprising a wooden member 10^a and metal facing member 10^b. The instrument board 10 is provided with an opening 11 extending therethrough in which 70 is positioned a panel 12 supporting various instruments and indicating devices such as are usually associated with the control of the automobile of which they form a part. The panel 12 is preferably made from relatively heavy sheet metal to a suitable shape such as is shown in Figure 5 and is provided with openings 13 for the reception of various instruments such as the clock 14, ammeter 15, oil gage 16, fuel gage 17 and 75 speedometers 18, and an opening 19 adjacent its top edge through which an electric lamp bulb 20 is adapted to project. The panel 12 is also provided with outwardly 80 projecting ears 21 struck back slightly from the plane of the face of the panel and provided with openings 22 for receiving fastening means such as the wood screws 23 which pass therethrough and into the rear face of the wooden portion 10^a of the instrument 85 board 10 for the purpose of securing the panel 12 thereto.

Each of the various instruments shown is 90 of the conventional type provided for single and independent mounting upon an instrument board and each is provided with an independent glass cover such as is indicated by the numeral 24 in Figure 8, and a bezel or face ring 25 which is of a size and shape to conform to the openings 13 in the panel 12 and projects therethrough. Each face ring 25 is provided with an inwardly turned radial flange 26 adapted to engage the front of the glass cover 24 and hold it against its respective instrument and an outwardly 100 turned radial flange 27 which is adapted to rest against the rear face of the panel 12 and prevent further forward movement of the instrument. Adjacent each instrument 105 and diametrically positioned in respect there- 110

to are two studs 28 secured to the panel 12 by any suitable means, but as shown are provided with so-called "flat" heads which seat in depressions formed in the front face of the panel 12. Clamping bars such as 29 extend across the back of each instrument and are received by the studs 28 and drawn down by nuts such as 30, or by a special form of nut as shown in Figure 8, which secures the instruments to the panel 12 with the face of the instruments projecting a slight amount past its front face. The nut 31 (Figure 8) which projects through an opening in the clamp bar 29 is provided with a conical head which when drawn down into position lies flush with the outer face of the bar 29. Formed with and extending up from the face of the nut 31 is a cone-like projection 32 which is provided with a screw driver slot 33 and surrounding the stud 28 from the panel 12 to the bar 29 is a tube 34 for preventing access to the nut 31 from below the bar 29. The method followed in the use of this construction is to assemble the parts as shown and screw the nut 31 down into position with a screw driver engaging the slot 33. Upon sufficient force being applied to the screw driver after the nut 31 has been screwed home, the projection 32 breaks off at its point of junction with the nut 31, leaving the exposed face of the nut 31 practically smooth and flush with the bar 29. This leaves no ready method of unscrewing the nuts 31 to remove the instruments, and such a construction is particularly desirable for use in securing valuable instruments to the instrument board as these instruments are especially sought by thieves.

Overlying the face of the panel 12 is the scroll, finishing, or face plate 35 which is shaped to conform to the opening 11 in the instrument board 10 and is provided with various openings 36 which receive the projecting front portions of the various instruments, the metal about the openings 36 being rearwardly flanged, as at 37 in Figure 2, and such flanged portion is received in the openings 13 of the panel 12. The outer edge or periphery of the scroll plate 36 is formed to present a forwardly extending flange portion 38 terminating in an outwardly flanged portion 39 against which rests a glass cover plate 40, of such a size and shape as to close the opening 11 and extend over the faces of all the instruments. A bezel ring 41 secured to the panel 12 by screws such as 42 or by other means extends forwardly therefrom and is provided with an inwardly extending reversely bent portion 43 forming a pocket which receives a deformable element 44, such as a rubber strip, which contacts against the forward edge of the glass cover plate 40 and causes it to bear against the outwardly flanged portion 39 of the scroll plate 36, securely holding the latter in prop-

er position between the panel 12 and glass 40. A finishing ring 45 closely fitting the bezel ring 41 is provided with an outwardly extending flanged portion 46 which effectively conceals the joint between the bezel ring 41 and the metal facing 10^b of the instrument board 10.

The upper part of the opening 11 in the wooden portion 10^a of the instrument board 10 is cut out to a greater extent than the metal face 10^b and the bezel ring 41 is provided with an upwardly extending pocket 47, which is concealed behind the metal face portion 10^b and into which projects the lamp bulb 20. The interior of the pocket 47 is preferably polished in order to better reflect the light from the bulb 20 on to the faces of the various instruments therebelow through the opening 48 cut in the upper portion of the flanged portion 38 of the scroll plate 36 immediately below the bulb 20.

Surrounding the opening 19 in the panel 12 and projecting rearwardly and downwardly therefrom is a sleeve member 49 whose forward outwardly flanged edge is secured to the panel by spot welding or other suitable means, and whose rear edge is provided with an inwardly turned flange portion 50. An outwardly extending groove is provided on the interior of the sleeve approximately midway its length and a washer 51 is positioned therein to acts as a stop for the coil spring 52 which extends between the same and a second washer 53 which normally is pressed against the inwardly turned flange portion 50. The bulb 20 is secured in a socket member 54 in a conventional manner and the socket member 54 is provided with two radially extending diametrically opposed pins 55 which are adapted to be received by notches 56 in the inwardly turned flange portion 50 of the sleeve 49. The openings in the sleeve 49 and washers 51 and 53 are large enough to admit both the bulb 20 and socket 54 therein which allows both the bulb and socket to be removed and reinserted from the back of the panel when it is desired to change a bulb. In positioning the bulb 20 and socket 54, the same are inserted within the sleeve 49, the pins 55 are passed through the notches 56 and are brought up against the washer 53 which is forced forward, compressing the spring 52, until the pins 55 are free of the notches 56 at which time the socket 54 is rotated to bring the pins 55 out of line with the notches 56 and the socket is then allowed to move back, the spring 52 causing the pins to be clamped between the washer 53, and the flange 50, thereby holding the lamp and socket in proper normal position.

A gasket such as 57 is preferably provided between the glass cover 40 and the flanged portion 39 of the scroll plate 36 to take up any unevenness in the joining surfaces,

and a gasket such as 58 is also preferably provided between the outwardly flanged portion 27 of the face rings 25 and the panel 12 to prevent entrance of dust therethrough on 5 to the face of the instruments and scroll plate.

It will be seen from the foregoing that the construction involved includes several novel features, the most notable of which 10 are perhaps the readily replaceable scroll plate, the concealed light pocket of the bezel ring, and the lamp and socket removable from the rear without dismantling the panel unit. The advantage of the removable scroll 15 plate as previously described is the ability to change the finish of the panel mounting to suit different finishes of instrument board, body interior, or other finishes. The advantage of forming the light pocket in 20 the bezel ring to lie behind and be concealed by the metal facing of the instrument board is that a neater and more artistic design of panel may thereby be obtained and the advantage of the lamp bulb and socket being 25 removable from the rear face of the panel is that such a method provides a quick and easy means of replacing a damaged bulb.

Although but one embodiment of the present invention is shown and described, it is 30 understood that the same is capable of various modifications and refinements, as for instance, the use of a two piece scroll plate comprising a rim and face portion instead of the one piece construction shown, without 35 departing from the spirit and substance of the broad invention, the scope of which is commensurate with the appended claims.

What I claim is:—

1. In combination with an instrument board having an opening therethrough, a supporting panel closing said opening, instruments supported by said panel, a removable finishing plate provided with openings through which said instruments are visible 40 overlying said panel, and a single glass cover overlying all of said instruments.
  2. In combination with a supporting element having an opening therethrough, an instrument supporting panel closing said opening, instruments supported by said panel, a separate finishing member overlying said panel provided with openings through which said instruments project, a single glass cover extending over the faces of all the instruments, and a bezel ring secured to said panel for clamping said glass cover and said finishing member in operative position.
  3. In combination with an instrument board provided with an opening, a supporting panel closing the rear face of said opening and secured to said board, and instruments having independent glass covers projecting through and supported by said panel, of a bezel ring secured to and projecting 50 55 60 65 70 75 80 85 90 95 100 105 110 115 120 125 130
- forwardly from said panel engaging the periphery of said opening, a glass cover extending over all of said instruments, and a finishing member for the face of said panel clamped between said bezel ring and said panel.
4. In combination with an instrument board provided with an opening, a panel secured to said instrument board overlying said opening, and instruments projecting through and supported by said panel, of a bezel ring secured to said panel terminating at its front edge in a reversely bent portion providing a pocket for a resilient gasket member, and a removable scroll plate and a panel cover glass clamped between said resilient gasket member and said panel.
  5. In combination with an instrument board having an opening therethrough, an instrument supporting panel closing said opening, and a plurality of instruments supported therein, a bezel ring supporting each of said instruments in said panel, a finishing plate adjacent the face of said instruments covering the exposed face of said supporting panel, a glass plate covering all of said instruments and said finishing plate, and a bezel ring secured to said supporting panel for clamping said glass plate and finishing plate in operative position.
  6. In combination with an instrument board having an opening therethrough, an instrument supporting panel closing said opening, and a plurality of instruments supported therein, a detachable finishing plate for said panel, a glass plate covering all of said instruments and said finishing plate, a bezel ring secured to said supporting panel for clamping said glass plate and finishing plate in operative position, and illuminating means supported by said supporting panel and concealed by said finishing plate for illuminating said instruments.
  7. In combination with an instrument board having a metal face portion and a backing portion, an instrument supporting panel mounted in an opening in said instrument board, instruments supported on said panel, a single glass cover extending over the faces of all of said instruments, and a bezel ring clamping said glass cover in position, said bezel ring being provided with an offset pocket concealed behind said metal face portion for receiving instrument illuminating means.
  8. In combination with an instrument board composed of a wooden back and a metal face, a symmetrical opening in said metal face, an opening in said wooden back matching said opening in said metal face provided with a cut-out portion projecting past the periphery of said opening in said metal face, a plate member supported by and flush with the rear face of said wooden back, indicating instruments projecting

- through and supported by said plate, a glass plate closing said opening in said metal face, and a bezel ring for holding said glass plate in position, said bezel ring being provided 5 with an outwardly extending pocket concealed by said metal face and lying in said cut-out portion of said wooden back for receiving illuminating means for said instruments.
- 10 9. In combination with an instrument board comprising a wooden back and a metal face having a symmetrical opening therethrough, an instrument supporting panel, a removable finishing plate adjacent 15 the front face of said instrument panel closing the opening in said wooden back, a glass plate closing the opening in said metal face, a bezel ring secured to said instrument panel supporting said glass plate and provided with a lamp-receiving pocket 20 positioned to be concealed by said finishing plate, a lamp positioned in said pocket, and means for supporting said lamp whereby it may be removed from said pocket without removing said bezel ring, glass plate, and 25 finishing plate.
10. In a device for supporting instruments to the instrument board of an automobile, the combination with an instrument supporting plate and a glass cover for said 30 plate, of a finishing plate detachably secured between the face of said plate and said glass, said finishing plate being held in operative position by pressure applied thereto by said glass. 35

Signed by me at Detroit, Michigan, U. S. A., this 26th day of Sept. 1924.

BENJAMIN H. ANIBAL.

DISCLAIMER.

1,585,636.—*Benjamin H. Anibal*, Detroit, Mich. INSTRUMENT PANEL. Patent dated May 25, 1926. Disclaimer filed November 19, 1927, by the assignee, *The Studebaker Corporation*.

Hereby enters this disclaimer to claims 6 and 10, to wit:

“6. In combination with an instrument board having an opening therethrough, an instrument supporting panel closing said opening, and a plurality of instruments supported therein, a detachable finishing plate for said panel, a glass plate covering all of said instruments and said finishing plate, a bezel ring secured to said supporting panel for clamping said glass plate and finishing plate in operative position, and illuminating means supported by said supporting panel and concealed by said finishing plate for illuminating said instruments.”

“10. In a device for supporting instruments to the instrument board of an automobile, the combination with an instrument supporting plate and a glass cover for said plate, of a finishing plate detachably secured between the face of said plate and said glass, said finishing plate being held in operative position by pressure applied thereto by said glass.”
